UNITED STATES PATENT OFFICE.

CIRIACHINO FURCOLO, OF PHILADELPHIA, PENNSYLVANIA, ASSIGNOR OF ONE-HALF
TO GIOVANNI PISCIRILLO, OF PHILADELPHIA, PENNSYLVANIA.

INVISIBLE RUBBER OR ATTACHMENT FOR SOLES.

Application filed July 16, 1923. Serial No. 651,929.

This invention relates to invisible rubbers or waterproof attachments for shoe soles. The principal object of the invention is to produce a rubber which will by its inherent 5 elasticity cling to the shoe sole and which when in place will not be noticeable as being separate from the shoe.

Another object is to provide a device of this nature with suitable invisible securing 10 means for firmly holding the device in place.

Another object is to suitably form the device so as to closely simulate the welt of a shoe.

Another object is to produce a device of 15 this nature which shall be simple of construction, cheap to manufacture, and highly efficient for the purpose for which it is designed.

With these and other objects in view as 20 will be more apparent, the invention consists in certain novel construction and combination and arrangement of parts, the essential features of which are hereinafter fully described, are particularly pointed out in 25 the appended claim, and are illustrated in the accompanying drawing, in which:—

Figure 1—is a top plan view showing the device as extended in the act of placing the same on a shoe.

Figure 2—is a transverse sectional view.

Figure 3—is a bottom plan view.

Like characters of reference refer to like parts in all views.

The present invention contemplates the 35 construction of a rubber covering for the soles of shoes which shall grip the shoe by its inherent resiliency and which shall be suitably secured to the shoe by substantially invisible securing means. I am aware that 40 there have been various attempts to attain similar ends, but in these prior devices, there has been incorporated a layer of fabric or metal which entirely did away with the elastic effect of the rubber coating, and the 45 securing devices have been such as stand away from the body of the shoe and either form an obstruction to the free use of the foot or else show in an unsightly manner.

Referring to the drawing in detail, 50 represents the body of my improved rubber covering for shoe soles, which is formed with an upstanding and inwardly projecting flange 11 which extends from the instep around the toe to the other side of the 55 instep. This flange 11 is provided upon its

upper surface with a plurality of extrusions or lugs 12 which are arranged so as to give the impression of the stitching of the welt. The entire shoe body and flange is made of 60 flexible and elastic rubber material so that it will stretch out to the position shown in Figure 1 in applying the device to the shoe.

After the flange 11 is brought into close contact over the top of the welt, it is then necessary that the device be secured to the 65 shoe. This securing means which I provide consists of a screw and a plate. At the ball of the foot, I insert a short screw 14 which holds the forward part of the device in 70 place. At the instep the flange 11 fades into the flat thin sole part which is extended up into the instep at 15. Across the end of this plain thin portion 15, I place a bar 16 which I secure to the shoe with three screws 17. Adjacent the centre of the bar the thick part 75 of the sole merges into a pointed portion to strengthen the centre of the sole, and from this pointed portion the sole proper curves laterally and partially forward, and from 80 the curved portions the sole merges into the flat thin sole part, which lies under the bar, and is thereby secured. Since the bar has its centre immediately adjacent the pointed portion the sole is held more secure and 85 strengthened at such point. In this manner, it will be seen that I have provided a positive securing means which is practically invisible and which offers nothing to catch and trip the wearer.

While I have described what I deem to 90 be the most desirable embodiment of my invention, it is obvious that many of the parts may be varied without in any way departing from the spirit of my invention, and I therefore do not limit myself to the exact details 95 of construction herein shown nor to anything less than the whole of my invention limited only by the appended claim.

What I claim is:—

An attachment for shoe soles comprising 100 a relatively thick rubber sole provided with an upstanding marginal flange about the major portion of said sole, excepting the terminals of said upstanding marginal flange which terminate a substantial distance from 105 where the sole lies adjacent the instep, whereby the side portions of the rubber sole may be flexed to permit easy removal of the rubber sole, said flange adapted to engage 110 with and overlie the marginal edge of a shoe 115

sole, said rubber sole at a point immediately adjacent the forward part of the instep merging into a relatively thick pointed portion, which strengthens the centre of the rubber sole, said rubber sole on opposite sides of the pointed portion being curved laterally and partially forward, and from the curved portions the sole fades into a flat thin sole part engaging with the forward part of the

instep, a perforated transverse bar engaging 10 with and overlying the flat thin sole part, and means adapted to penetrate through the bar and the thin flat sole part and into the shank of the shoe sole, to secure the parts together. 15

In testimony whereof, I affix my signature.

CIRIACHINO FURCOLO.
